MAGAZINE STOVE

Oliver T. Tindell, Jr., Chattanooga, Tenn.

Application November 25, 1942, Serial No. 466,894

5 Claims. (CL 126—73)

1

This invention is a domestic heating stove, for burning coal particularly; wood or other fuels, could of course, be used.

The stove is of the type having a fire pot forming a fuel magazine of good size, and the principal object of the invention is to provide a stove which by reason of adequate feed of primary and particularly of secondary air, will make a hot fire fairly quickly, and which, particularly by reason of the feed of secondary air into the fire pot, will burn coal that in some stoves is difficult to burn, namely, certain types of bituminous coal and coal containing rock, slate and "bone."

According to this invention, the fire pot, which is preferably made of fire brick, although it could be made of cast iron, is provided with vertical slots or passages for secondary air. The fire pot is supported on an apertured ring, the vertical passages being in registry with corresponding apertures in the supporting ring, so that secondary air can pass through the apertures in the ring into these vertical slots or passages, thereby becoming preheated, and thence into the fire, aiding combustion and aiding in the burning up and consumption of smoke.

The fire pot may also be provided with another feed for secondary air, by providing the fire brick with lateral holes or passages therethrough, and by spacing the fire brick inwardly of the metallic casing so that there is a space back of the fire brick lining. Secondary air is supplied to these spaces behind the fire brick lining, becomes preheated, and then passes inwardly through the lateral passageways into the fire, also aiding combustion and serving to help consume the smoke.

One of the important features of the invention is that the apertured ring, supporting the fire brick lining, is in turn supported by a number of hollow brackets which are open at the top and bottom and so provide an independent supply of secondary air to the space behind the fire brick from whence this secondary air, which by this time is preheated, passes laterally into the fire pot.

Another feature of the invention is a controlled air inlet baffle in the upper back part of the stove, for admitting additional air for combustion and for baffling the heat.

Further details and advantages of the invention will be described in connection with the accompanying drawings, illustrating the present preferred structure.

In these drawings:

Fig. 1 is a vertical sectional view through a stove in accordance with the present invention;

2

Fig. 2 is a section on the line 2—2 of Fig. 1;

Fig. 3 is a section on the line 3—3 of Fig. 1;

Fig. 4 is a horizontal fragmentary section through one of the supporting legs;

Fig. 5 is a perspective view of a portion of the fire brick lining;

Fig. 6 is a sectional view of a modification, showing an air inlet baffle in the top of the stove;

Fig. 7 is a fragmentary elevation on line 7—7 of Fig. 6; and

Fig. 8 is a fragmentary section on line 8—8 of Fig. 6.

Referring now to these drawings, the stove comprises a base plate 2 which supports a cylindrical sheet metal body portion 4 and is in turn supported by a base member 6 and legs 8. The base plate 2 forms the bottom of an ash pit 10, access to which is had through a conventional door 12 provided with the usual damper 14. Supported by the base plate 2 is a number of hollow supporting brackets 16, which are substantially U-shaped in cross section, as shown particularly in Fig. 3, and which are held in place by bolts 18, passing through the legs 8. As shown particularly in Fig. 1, the hollow brackets 16 register with air inlet apertures 20 in the base plate and provide channels or ducts for forming an independent supply of secondary air, to be described later.

The brackets 16 in turn support an apertured ring 22 which is a skeleton type of ring in that it is provided with a series of long and short apertures 22a and 22b, all the way around the ring. The ring 22, in addition to supporting a conventional grate consisting of a ring 24 and grate bars 26, also supports a fire pot, indicated generally at 28, and consisting preferably of fire bricks 30 provided with grooves 32 along their vertical edges and with offset shoulders or ribs 34, assembled to form a circular fire pot open at the top and bottom.

Referring particularly to Fig. 5, adjacent grooves 32 cooperate to form vertical passages 36 for secondary air, extending around the fire pot.

The fire bricks are placed on the supporting ring 22 so that the vertical passages 36 register with one of the large apertures 22a, whereby secondary air passes upwardly through the slots 22a, thereby becoming preheated, and thence upwardly in the passages 36 and into the fire.

The external ribs 34 serve to space the fire brick inwardly from the body 4, thereby providing vertical air spaces or channels 38 back of the fire pot, for secondary air, secondary air being supplied to these air channels by the hollow

air feeding brackets 16, already described. Some secondary air passes into these spaces from the ash pit 10. This secondary air becomes preheated and passes inwardly from the spaces 38 through apertures 40, preferably tapered inwardly as shown, but which may be of any suitable shape, and thence inwardly into the fire pot, aiding combustion and smoke consumption.

If desired, the lower portion of the casing 4 enclosed within the upper part 8' of the legs 8, 10 may be provided with holes 42 for feeding additional secondary air into the hollow brackets 16. However, such holes are optional and may be omitted if desired.

Mounted on the upper, inner edge of the fire pot 38 is a supporting ring 44, the outer edges of which may be spaced inwardly from the top element 46 of the stove to allow some of the secondary air from spaces 38 to pass into the space 48 in the top of the stove. The stove is completed by a conventional top member 50, feed door 52, smoke pipe 54, and damper 58.

In operation, primary air passes upwardly through the grate 24, 26 as usual. Secondary air passes upwardly through apertures 22a into the vertical passages 36 and thence into the fire pot. Additional secondary air passes up through the hollow brackets into the space back of the fire pot and thence through holes 40 into the fire pot. Some of this secondary air may pass around the outer edge of ring 44, into the space above the fire pot.

All of the secondary air, by the time it reaches the fire, is well preheated, thereby aiding combustion and smoke consumption. The supply of preheated secondary air also enables the stove to make a quick "pick-up" after the drafts are opened after it has been banked.

By opening the drafts, the stove of the present invention has been found capable not only of burning ordinary coal, but also of burning coals which are more difficult of combustion, such as certain types of bituminous coal and coals containing rock, slate and "bone." However, by throttling down the drafts, a slow fire may be maintained for a long time. By filling the fire pot with coal, and shutting the drafts, the stove may be banked for long periods.

The stove of the present invention has been subjected to impartial competitive tests at the Bureau of Standards. In these tests, the fire was kindled with wood and coal and burned for a half hour. Then the fire pot was fully charged with coal. With the drafts open, the fire "broke through" at the top of the fire pot 2 hours and 20 minutes later. Burning was continued, and a stack temperature of 900° F. was reached 2 hours and 5 minutes after the break through. These tests were made with bituminous coal.

In another test, 50 lbs. of bituminous coal was put on a bed of coals and the stove banked by closing the drafts. Twelve hours later, the drafts were opened, and the stove "picked up" in 25 minutes.

Figs. 6, 7 and 8 show a modification which may, if desired, be used in connection with the features already described. Referring to these figures, parts corresponding to the parts in Figs. 1-5 are correspondingly numbered. The air inlet heat baffle of this modification comprises a flattened tubular member 56, open at both ends, the rear end being in registry with an air inlet opening 58 in the back of the stove, which opening is controlled by a conventional damper 60. The front end of the member 56 forms an air

70 delivery opening 62, in any desired shape, which delivers additional air for aiding combustion of unburnt gases in the top of the stove. Member 56 also baffles the heat, preventing too rapid escape of the hot gases up the stack, and tends to hold the heat in the top of the stove and to lower the stack temperature. By controlling the fire box damper 14, and the top dampers 58 and 60, the primary and secondary air may be varied over a wide range, with a corresponding range in the combustion rate of the stove. The baffle member 56 is subjected to radiant heat from the fire pot and to heat from the hot gases passing up the stack, and so air entering through member 56 is well preheated when it enters the top of the stove. Preheated secondary air admitted through the member 56 cooperates with preheated secondary air that passes over the outer edge of the ring 44, in completing the combustion of any unburnt gases in the top of the stove.

20 While the stove of the present invention has been described in considerable detail, it should be understood that the invention is not limited to the precise details shown, but may be carried out in other ways.

I claim as my invention:

1. A domestic heating stove, comprising a metallic body, an apertured supporting ring in the lower part of the body, a grate through which the primary air may pass, supported by said ring, a fire brick lining supported by said ring, said lining having vertical slots opening on the inside of said fire brick lining for directing secondary air into the fire pot, registering with corresponding apertures in the supporting ring, said fire brick lining being also provided with lateral passages through which secondary air may pass and with ribs for spacing the lining inwardly of the metallic body to define vertical channels for secondary air and hollow brackets, open at the top and bottom for supporting said apertured ring and for directing secondary air to said vertical channels, from whence it may pass inwardly through said lateral passages into the fire pot.

2. A domestic heating stove, comprising a metallic body, an apertured supporting ring in the lower part of the body, a grate through which the primary air may pass, supported by said ring, a fire brick lining supported by said ring, said lining comprising fire bricks having lateral passages therein said fire bricks being grooved and shouldered to define vertical air passages on the inside of the fire pot and to define vertical ribs on the outside of the fire pot, said ribs serving to space the fire brick inwardly of the metallic body, to form vertical channels for secondary air just outside said fire brick lining, the vertical passages in the fire brick lining registering with corresponding apertures in the supporting ring, said vertical passages being adapted to receive secondary air and to direct it into the fire pot, and hollow brackets, open at the top and bottom, for supporting said ring and for directing secondary air to said vertical channels, from whence it may pass inwardly through said lateral passages into the fire pot.

3. A domestic heating stove, comprising in combination a metallic body, an apertured ring mounted in the lower part of said body, a fire pot supported by said apertured ring, said fire pot being composed of fire bricks provided with means defining inner vertical grooves and outer vertical ribs, said grooves defining air supplying passages on the inside of the fire pot communicating with

the apertures in the apertured ring for receiving air therefrom, and directing such air into the fire pot, said ribs serving to space the fire bricks inwardly from the metallic body to define vertical channels for secondary air between the bricks and the metallic body, hollow brackets for supporting said apertured ring and for directing secondary air to said vertical secondary air channels, and means for directing secondary air from said vertical channels into the fire pot.

4. A domestic heating stove, comprising in combination a metallic body, an apertured ring mounted in the lower part of said body, a fire pot supported by said apertured ring, said fire pot being composed of fire bricks provided with means defining inner vertical grooves and outer vertical ribs, said grooves defining air supplying passages on the inside of the fire communicating with the apertures in the apertured ring for receiving air therefrom, and directing such air into the fire pot, said ribs serving to space the fire bricks inwardly from the metallic body to define vertical channels for secondary air between the bricks and the metallic body, hollow brackets for supporting said apertured ring and for directing secondary air to said vertical secondary air channels, and means for directing secondary air from said vertical channels into the space above the fire pot.

5. A domestic heating stove, comprising a metallic body, an apertured ring in the lower part of the body, a fire pot supported on said ring and provided with vertical grooves on the inside thereof and with passages therethrough through which

secondary air may pass, means for spacing the fire pot inwardly of the metallic body to define an air space therebetween, which communicates with said passages through the fire pot, the vertical grooves on the inside of the pot registering with the apertures in the ring and being adapted to receive secondary air therefrom and to direct it into the fire, and hollow brackets, open at the top and bottom, for supporting said ring, and for directing secondary air to said air space, from whence it may pass through said passages in the fire pot and thence into the fire.
